UNITED STATES PATENT OFFICE

WILSON R. SPRINGER, OF OSKALOOSA, IOWA

FACIAL CHANGE DEVICE FOR DOLLS

Application filed March 24, 1930. Serial No. 438,450.

The object of my invention is to provide a facial change mechanism which can be used for dolls or the like and which is of simple, durable and comparatively inexpensive construction.

A further object is to provide for a doll head or the like having eye and mouth openings therein a facial change device consisting of rotatable members, each provided with a plurality of variously expressed features thereon, with a weighted means for rotating the rotatable members which may be operated by tipping the doll head whereby the variously expressed features on the rotatable members are successively exposed to view through the eye and mouth openings of the doll head.

Still a further object is to provide a modified construction in which a manually movable member may be manipulated for causing changes in the expression of the doll.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

30 Figure 1 is a front elevation of a doll head illustrating one expression on the face thereof.

Figure 2 is a similar reduced view illustrating another expression.

35 Figure 3 is an enlarged sectional view on the line 3—3 of Figure 1 illustrating the facial change mechanism in section.

Figure 4 is a front elevation of the mechanism apart from the doll head.

40 Figure 5 is a side elevation of Figure 4 viewing the mechanism in the direction of the arrow 5 adjacent Figure 4 and

45 Figure 6 is a sectional view similar to a part of Figure 3 illustrating a modified form of construction.

50 On the accompanying drawings, I have used the reference numeral 10 to indicate a doll head or the like. Eye openings 12 and a mouth opening 14 are formed in the head 10.

My facial change mechanism consists of a pair of frame members 16 adapted to be supported within the doll head 10, as shown in Figure 3. For instance, ears 18 on the ends of the frame members 16 may be embedded in the material of the head.

A pair of shafts 20 and 22 are rotatably carried by the frame members 16. Eye members 24 are secured to the shaft 20 in any desirable manner.

Eyes, as indicated by the reference characters *a* and *b*, are represented on the eye members 24 at spaced circumferential points. As indicated at *c* a blank space may be left if desired.

Secured to the shaft 20 between the frame members 16 is a ratchet wheel 26. For rotating the ratchet wheel 26 I provide a pawl 28 pivoted to a pin 30. The pin 30 is connected to a U shaped weight frame 32. The weight frame 32 is pivoted at 34 to the frame members 16.

Stops 36 and 38 are provided for the weight frame 32 to limit swinging movement thereof. A weight 40 is carried by the weight frame 32. Normally the weight assumes the position shown in full lines in Figure 3 with the weight frame 32 against the stops 36. When the doll is tipped backward to a horizontal position, however, the weight 40 will swing to the dotted line position illustrated so that the pawl 28 may engage another tooth of the ratchet 26 for rotating it another portion of a revolution. The represented eyes *a* and *b* are arranged on the eye members 24 so as to successively appear in the eye openings 12 as the doll head is tipped back and forward.

An operative connection is provided between the shaft 20 and the shaft 22. On the drawings, I have illustrated bevel pinions 42 and 44 and a gear 46 meshing with the pinions. A mouth member 48 is secured to the shaft 22 and has various represented mouths *a'*, *b'* and *c'* etc. thereon for showing through the mouth opening 14.

It will be obvious that the facial expression of the doll head can be easily changed by merely tipping the doll and with the number of represented eyes and mouths on

the members 24 and 48 shown, a great variety of expressions can be given to the doll's face.

When the blank spaces *c* appear through the eye openings 12 the doll will be apparently asleep.

In Figure 6 I have illustrated a modified construction in which the pawl 28 is pivoted to a lever 50. The lever is pivoted at 52 and connected by a link 54 with a push-button 56. A spring 58 is provided for holding the pawl at one limit of its movement. This form of device may be manually operated by pressing the button 56 which is located in a socket 60 formed in the head 10. Thus it will be seen that the device can be either arranged for automatic operation by tipping the doll or manual operation when arranged as shown in Figure 6.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. For use with a doll head having a plurality of openings therein, a facial change device comprising movable members, each provided with a plurality of variously expressed features thereon and discernible through said openings, means to move one of said members and an operative connection between said last mentioned member and another of said members comprising pinions associated with said members and a gear meshing with said pinions.

2. For use with a doll head having a pair of eye openings and a mouth opening therein, a facial change device comprising a pair of rotatable members for said eye openings and a member for said mouth opening, each of said members being provided with a plurality of variously expressed features thereon discernible through said openings and weight means, operable by tipping said doll head, for rotating said pair of members from one feature to another, a pinion associated with said pair of members, a pinion associated with said third member and a gear meshing with said pinions for rotating said third member from one feature to another simultaneously with the operation of said pair of members.

3. For use with a doll head having a plurality of openings therein, a facial change device comprising movable members, each provided with a plurality of variously expressed features thereon and discernible through said openings, means to move one of said members and an operative connection between said last mentioned member and another of said members comprising bevel

pinions associated with said members and an angularly arranged gear meshing with said pinions.

Des Moines, Iowa, March 15, 1930.

WILSON R. SPRINGER.
